UNITED STATES PATENT OFFICE.

ERNEST E. MINARD, OF DETROIT, MICHIGAN.

SHADE GUIDE.

Application filed May 13, 1925. Serial No. 29,905.

The screening of openings in porches and verandas and also the doors of houses such as summer cottages is often effected by means of canvas or similar curtains, and it is very desirable that such curtains or screens should be of a more or less permanent nature and at the same time capable of being moved into and out of operable positions with respect to the openings with which they are associated, but difficulty has usually been found in providing for the proper support of the screens when extended over the openings so that in the case of porches and verandas they will be effectively held against undesirable flapping or distortion by wind, and in the case of indoor openings against inadvertent movement from their closed positions such as renders the ordinary hanging or curtain inadequate for its purposes.

This invention, therefore, proposes to overcome the objectionable features ordinarily present in the use of screens as heretofore commonly employed for the said purposes, and to provide a simple and effective method of mounting screens in openings so that they may be readily moved into and out of operative positions and at the same time when in operation be held laterally in such manner that they will afford ample protection against the passage of wind or rain through openings screened thereby.

A further object is to effect the incorporation of the edges of such a screen in the frame of the opening and the retention of such edges therein whereby the passage of wind or rain therearound is prevented or minimized, and whereby tension is exerted on the curtain offering a resistance to the warping effects of wind pressure thereagainst.

Still further objects subsidiary to or resulting from the aforesaid objects, or from the construction or operation of the invention as it may be carried into effect, will be apparent as the said invention is hereinafter further disclosed.

In carrying the said invention into effect, I may utilize hollow or tubular posts, as the lateral members of the frame of the opening to be screened, and house a flexible screen upon a roller enclosed in a suitable housing at one end of the frame, means being provided for the operation of the roller such as the equivalent of means commonly employed in the spring rollers of blinds. The posts are formed with opposed longitudinal slots

in which the marginal portions of the screen are guided and through which such marginal portions are adapted to extend into the hollow posts, these slots being provided with guide rails on the inner sides of which suitable retaining means such as rings carried by the margins of the screen ride. One of these sets of rails may be movable transversely of its post and relative to the opening so that lateral tension may be exerted on the said screen when in its drawn position, adjustable resilient means being employed to effect the retraction of such rails and the provision of such tension on the screen.

All of which is more particularly described and ascertained hereinafter, by way of example, having reference to the accompanying drawing, wherein,—

Figure 1 is a perspective view of a portion provided with screens embodying the said invention;

Figure 2 is a fragmentary elevation of a window frame and screen mounted therein in accordance with the said invention;

Figure 3 is a section of the same taken on the line 3^x—3^x, Figure 2; and

Figure 4 is a vertical section of the same taken on the line 4^x—4^x, Figure 2.

Similar characters of reference indicate similar parts in the several figures of the drawing.

1 indicates a structure provided with spaced posts 2 and 3, these posts being hollow or tubular and provided with opposed slots 4 and 5 respectively extending in the direction of their length. At the top of the opening is a cross piece 6, and at the bottom a hollow sill or housing 7, the upper part of which is provided with a slot 8 extending between the lower ends of the aforesaid slots 4 and 5 in the hollow posts. This housing accommodates a roller 9 upon which a blind, screen or curtain 10 is adapted to be wound, the said roller being provided at one end with a pulley 11 from which a weight 12 is suspended by a flexible member 13 so that the said weight will effect the rolling of the screen upon the said roller as will be quite apparent without further description.

The outer end of the screen 10 is provided with a cord 14 passing around a clutch roller 15, whereby the curtain may be adjusted relative to the opening and secured in adjusted positions as will be also well understood.

It will be seen that the marginal portions of the screen extend substantially into the slots of the posts, the screen being wider than the opening, and these marginal portions are provided with rings or projecting members 16 which are engaged by guides or rails 17 and 18 within the slots 4 and 5 respectively of the said posts so that the marginal portions of the screen are prevented from being withdrawn laterally from the slots and whereby the screen is guided in its opening and closing movements.

When the opening is closed by the screen, it will effectively prevent or minimize the passage of wind or rain through the said opening more especially as the marginal portions of the screen are enclosed by the posts in the manner described, but an objectionable feature which is quite common to flexible screens, particularly when they are made of textile materials which are of a flexible or more or less flaccid nature and in some cases liable to stretch to some extent upon continued use, is the fact that such screens have an objectionable tendency to flap or warp under the influence of wind pressures or to be otherwise bulged or varied in their prescribed relation to the opening which is screened. This I effectively overcome by movably mounting the rails 18 in the post 3 and applying lateral tension to the screen through the said rails. In the example illustrated this is accomplished by mounting the rails 18 between the arms 19 of U-shaped members 20 housed in the said post 3, these U-shaped members being attached to rods 21 through which springs 22 effect a pulling force upon the said U-shaped members and incidently upon the screen through the medium of the rails 18.

The said rod is provided with an adjustable abutment 23 adapted to engage a suitably arranged stop 24 to prevent the movement of the said rails forwardly of the said opening to an undesirable extent, and the U-shaped members 20 may yieldably engage the inner sides of the posts so that they will frictionably damp or reduce the too free actuation of the said spring operated members where such damping is thought necessary or desirable.

The tensional arrangement permits of the operation of the screen as required for the opening and closing thereof, at the same time exerting sufficient tension on the said screen to counteract the tendency of wind pressure to bulge or warp the same in an objectionable manner or to set up vibrations or flapping such as is frequently observed in screens as commonly employed in veran-

das, porches, sun rooms and so forth; and the general arrangement suggested forms a much more workmanlike adaptation of screens to buildings than is usual, greatly adding to the comfort of dwellers, being readily adjustable to meet different weather conditions, and efficiently fulfilling the purposes for which it is intended.

This invention may be developed within the scope of the following claims without departing from the essential features of the said invention, and it is desired that the specification and drawing be read as merely illustrative and not in a limiting sense, except as necessitated by the prior art.

What I claim is:—

1. Means for the screening of an opening, comprising slotted tubular posts at opposite sides of said opening, an extensible screen wider than and adjustably mounted at one end of said opening, the margins of said screen being adapted to traverse the slots of said posts in the adjustment of said screen, and resiliently yieldable means exerting tension transversely of said screen.

2. A device according to claim 1, wherein the last mentioned means are carried by one of the said posts.

3. Means for the screening of an opening comprising slotted tubular posts at opposite sides of said opening, rails within the slots of said posts, an extensible screen, the margins of which are adapted to traverse the slots of said posts, means on the margins of said screen slidably engaging and guided by said rails, said rails being movable for the purpose of exerting transverse tension on said screen, and resilient means effecting such movement of said rails.

4. Means for the screening of an opening, comprising slotted tubular posts at opposite sides of said opening, rails within the slots of said posts, an extensible screen the margins of which are adapted to traverse the slots of said posts, means on said margins slidably engaging and guided by said rails, means movably supporting the rails of one of said posts therewithin, and resilient means exerting a pull on said supporting means which is transmitted to said screen and exerts transverse tension thereon.

5. Means for the screening of an opening according to claim 3, and frictional means damping the movement of said movable rails.

6. Means for the screening of an opening according to claim 3, and means adjustably limiting the opposite movement of said rails.

In testimony whereof I affix my signature.

ERNEST E. MINARD.
